UNITED STATES PATENT OFFICE.

REINHARD MÜLLER, OF ELM, NEAR CASSEL, GERMANY.

WRITING INSTRUMENT.

Application filed March 7, 1924. Serial No. 697,610.

To all whom it may concern:

Be it known that I, REINHARD MÜLLER, residing at Elm, near Cassel, Germany, have invented certain new and useful Improvements in Writing Instruments, of which the following is a specification.

This invention relates to writing instruments such as pen-holders, writing holders and writing pens of all kinds, in which the pen nib, adjustable to various angles, is arranged in an angle boss lying before the fingers of the hand so that it is held in a position deviating from the axis of the holder. In such writing instruments the holder boss always takes various angular positions according to the angular adjustment of the pen nib, when the nib is in its correct writing position, that is with the concave side downwards. The possibility of using the writing instrument for different kinds of writing follows directly on these different angular positions of the boss.

This invention has for its object to give the writing instrument the power to go over automatically to the position which the angular adjustment of the nib for the time being requires for the proper writing position, so that the writing instrument is in and only in the position of stable balance. By this means the handling of the instrument is considerably eased, since the hand tires when the instrument must be forcibly held the whole time in the proper position. In order to relieve this, pen-holders have already been made angular and equipped with a number of even surfaces, corresponding with the various angular positions of the boss, handling, however, being again, in another way, disturbed and apart from this, the tendency of the holder to leave the proper writing position, it will be understood is also not removed.

In order to produce this self-acting power of the writing instrument to go over steadily into the necessary position corresponding with the writing adjustment, the pen according to the invention is so adjustably arranged that its point on turning round the bearing axis of the nib describes a small circle about the point of intersection of the gravity axis of the instrument with the bearing axis of the nib.

A fuller explanation will now be given

with reference to the accompanying drawings.

Figure 1 is an elevation.

Figures 2 to 5 are cross sections.

Figures 6, 7 and 8 are elevations of the nib.

Figure 9 is a cross section on the line 9—9 of Figure 1.

Figure 1 shows the instrument which comprises a holder *a* (shown broken off) and a nib *c*. *b* is the known angle boss in which the nib *c* is carried. For this purpose a pin *d* shown in dotted lines, is mounted in a larger cylindrical bore so that an annular slot is formed in which the shaft of the nib *c* is fitted. The depth of entry in the example shown is limited by a band *f* on the nib *c* so that the nib point always stands out sufficiently from the boss *b*.

In Figure 1 it is assumed that the boss *b* is turned directly upwards and that the nib *c* is in the proper writing position, that is, with its concave side underneath facing the writing surface *x*. The gravity axis of the writing instrument, which owing to the boss *b* is somewhat displaced from the central axis of the holder shaft *a*, is indicated by *y* and the point of intersection between the bearing axis of the nib *c* with the gravity axis is indicated by *z*. If the nib *c* be given successively the various angle positions, so that it finally describes an angle of 360° about its bearing axis, the point of the nib passes through a small circle having the intersection point *z* as its centre. (This small circle should really appear in Figure 1 as a straight stroke, but for the purpose of illustration is shown as a small ellipse).

In Figures 2 to 5, are shown in section on the line 2—2 the four chief positions of the writing instrument. In Figure 2, as in Figure 1, the grip *b* is perpendicularly upwards. In Figure 3 the grip is turned through 90° so that it lies in the right hand side of the holder axis. In Figure 4, in which the grip has been turned through a further 90°, it is pointing perpendicularly downwards. In Figure 5 the grip turned through yet another 90° lies to the left side of the holder axis. The pen nib is in all these figures shown dotted, so that

its position can be seen. Above all, the nib is in the proper writing position, that is with it concave side downwards. The nib point rests on the writing surface; the 5 gravity axis of the instrument appears as a point y .

As is evident, the gravity axis in all 10 positions of the instrument is behind the nib point, and therefore behind the point of support around which the instrument can swing if held loosely in the hand. Should the holder by mistake be held in any other position, so that that boss has a direction other than that corresponding to the 15 particular angular position of the nib, then the instrument would automatically swing into the corresponding position, since only in this position is stable balance possible. If, for example, the nib were inserted as 20 in Figure 4, but the grip turned in an upward direction as in Figure 2, so that the concave side were turned wrongly, namely, in an upward direction, then the gravity axis y would be above the point of support, 25 that is above the point of the nib; the instrument would be in stable balance but at the least movement would tend to swing round, so as to take up the proper writing position for the nib corresponding to Figure 2.

An important point is the arrangement 30 of the nib which ensures a proper projection of the nib point, and so that the point is constrained to describe a circle in passing through the various angle positions; various

means can naturally be used for this. For 40 ensuring the projection, a band on the nib, as already described, and as shown in Figure 6, is a simple method. For allowing the nib point to be turned through a circle 45 a method ready to hand is the well known cylindrical pin d and annular slot described above. In order to hold the nib firmly in this slot for each position, a pressed out tongue can be formed in the shank of the nib as shown in Figure 6. For securing the correct amount of projection of the nib point, it will also suffice to provide a mark 50 on the shank of the nib which shows the correct depth of insertion. In order to use the same nib for a number of holders, which require different depths of insertion, a nib according to Figure 7 may be used having 55 several marks preferably numbered, for indicating the depth of the insertion.

Having now particularly described and ascertained the nature of my said invention and in what manner the same is to be performed, I declare that what I claim is:

A writing instrument embodying a holder and a nib, the holder having a boss at an angle to the longitudinal axis of the holder, the gravity axis of the instrument being in all positions of the instrument behind the nib point and also behind the point of support around which the instrument can swing if loosely held in the hand.

Dated this 15th day of February, 1923.

REINHARD MÜLLER.
